UNITED STATES PATENT OFFICE.

CARL WOODBURY, OF LOS ANGELES, CALIFORNIA.

DESIGN FOR A DUST-CAP.

53,172.

Specification for Design.

Patented Apr. 1, 1919.

Application filed January 11, 1919. Serial No. 270,744. Term of patent 14 years.

To all whom it may concern:

Be it known that I, CARL WOODBURY, a citizen of the United States, residing at Los Angeles, in the county of Los Angeles and State of California, have invented a new, original, and ornamental Design for Dust-Caps, of which the following is a specification, reference being had to the accompanying drawing, forming part thereof.

Figure 1 shows an elevation of the ornamental dust cap for the valve stem of a pneumatic tire; and

Fig. 2 shows a bottom plan view thereof.

What I claim is:

The ornamental design for a dust cap, as shown.

In testimony whereof I affix my signature.

CARL WOODBURY.
